UNITED STATES PATENT OFFICE.

CHARLES A. DRESSER, OF GREENBURG, NEW YORK, AND EDWIN W. HAMMER, OF SOUTH ORANGE, NEW JERSEY, ASSIGNEES TO CLINE ELECTRIC MANUFACTURING COMPANY, OF CHICAGO, ILLINOIS, A CORPORATION OF ILLINOIS.

TENSION DEVICE FOR NEWSPAPER-ROLL STANDS.

Application filed November 23, 1926. Serial No. 150,213.

This application takes the place of, and supersedes, our former application, Serial No. 741,534, filed October 4, 1924, in which was disclosed that portion of our present invention which relates to the maintenance of high generator output as the web-roll speed falls off when the press is decelerated.

In the drawing Fig. 1 illustrates an end view of a newspaper roll stand with which have been combined our novel tension devices; Fig. 2 is a diagram assisting to an understanding of our invention. Fig. 3 is a diagram showing an alternative method of connection.

High speed printing presses of the type employed in printing newspapers and the like are usually supplied with a web of paper drawn by the press from a large roll weighing in the neighborhood of 2000 pounds. This paper runs at a high rate of speed, 1200 feet per minute, more or less, and the heavy rolls of paper consequently rotate at high speed and with great momentum. With these high speed presses it is frequently the practice to mount a plurality of these large rolls of paper upon a roll stand so arranged that as one roll becomes depleted a second roll may be brought into operative position by the partial rotation of the reel of such roll stand, the depleted roll being then removed and a fresh roll substituted for it. While our invention is especially designed for use with such a roll stand it is also adaptable to the decker type of presses, without rotatable roll stands.

As is well understood in this art, the weight and speed of rotation of the rolls of web paper introduce a condition which is frequently troublesome in that the momentum of the rapidly rotating and heavy roll of paper will tend to persist when the press is to be stopped, causing an overrunning of the web sheet with a tendency to flood the press with loose paper. This occasions loss of time and material.

It is the object of our invention to overcome this tendency of the web roll to overrun when the press is stopped or is having its speed reduced, possibly in anticipation of shut-down, and the preferred means selected by us for accomplishing this purpose are illustrated in the accompanying drawings in which Fig. 1 represents an end elevation of a roll stand for a printing press

which includes a rotatable reel upon which are mounted a plurality of rolls of web paper. In connection with the roll stand we employ a frame suspended at its upper end and carrying two pulleys, one at either end of the frame, with an endless belt extending between and over these two pulleys. The frame with its pulleys and belt is so located that one side of the belt may rest by gravity against the surface of the active roll of paper and derive power therefrom. The greater the amount of power absorbed by the belt from the rotating paper the greater will be the drag or braking effect upon the roll of paper.

According to our invention the shaft driven by the upper pulley is connected to a dynamo electric generator which is thus driven by the rotation of the active roll of web paper. Under normal conditions the current generated by the dynamo electric machine is determined and absorbed, as by the placing of a fixed resistance across the armature terminals at a pre-determined strength of field magnetism. We prefer to use a separately excited generator for this purpose although we do not wish to limit ourselves in this respect.

As is well known, the usual high speed printing press is electrically driven and is electrically controlled by the press operator who has available certain switch buttons through which he can regulate the operation of the press including the stopping of the press quickly in case of emergency. According to our invention we connect one of the elements of the generator, either field or armature, through the press control devices in such a manner that the actuation of the press-stopping switch, for example, will change the electrical conditions of the generator to permit it to absorb more mechanical energy from its driving belt and connecting roll of web paper, thus increasing the braking effect of the traveling belt which rests upon such roll. Fig. 2 of the drawings shows a schematic arrangement for effecting this result. It will be understood that there may be a plurality of controls from the press to meet conditions imposed by stopping or merely decelerating the press; or the same or similar regulating devices may be actuated when the press is to be stopped or merely decelerated.

100
105

Referring particularly to the drawings, Fig. 1 shows an end view of a roll stand for printing presses comprising a reel mounted on pedestals 2 and carrying near its ends 5 a set of roll supporting arms 3 adapted to receive rolls of paper 4. The position of the rolls is controlled by an electric motor 7 which through suitable gearing engages with the gear wheel 7^a attached to the shaft 1. 10 The margin of the printed page is regulated by another motor 8 arranged to shift the shaft 1 with its arms 3 and paper rolls 4 longitudinally in its bearings.

Fig. 1 also shows a frame 12 pivoted at its 15 upper end and carrying pulleys 12^a and 12^b around which is passed a belt 9, such belt resting against the surface of the roll 4 from which the web 4^a is being drawn into the press. As will be understood from this 20 drawing, the frame 12 is mounted upon the shaft 10 but the only power for such shaft 10 is the power supplied by the belt 9 through the contact of such belt with the rotating roll 4 of paper. The frame 12 may 25 be provided with an eye 13 to serve as a means for withdrawing the belt 9 out of contact with the roll. The shaft 10 is supported in bearings 11. Driven by the shaft 10 is a dynamo electric generator 14 adapted 30 to absorb the mechanical energy transmitted through the frictional contact of the belt 9 with the active roll of web paper. In Fig. 2 we have shown, diagrammatically, the generator 14 with its armature A and field 35 magnet winding F. The armature is shown with its commutator brushes connected to a resistance R₁ while the field magnet winding is illustrated as in series with a resistance R₂. The resistance R₂ may be 40 short-circuited by a switching device M, the winding of which should be energized when the control button on the press is actuated, as to stop the press. It will be understood 45 that such actuation is to result in the short circuiting of the rheostat R₂ which will give a material increase in generator field magnetism with a consequent increase in current supplied by the armature A to the rheostat R₁. If, however, as indicated above, it be 50 desired to manipulate the circuit of the armature A of the generator 14, instead of the field magnet winding F of such generator, it is only necessary to disconnect the circuit closing contacts of the switching device M of Fig. 2 from the terminals of the 55 resistance R₂ and connect such contact terminals so as to short circuit all or part of the rheostat R₁ when the switching device M is actuated through the press control circuits. The effect of such short circuiting of the resistance R₁ will be to increase the generator output and thereby impose an added load to the belt 9 for the frictional 60 control of the web-roll 4. At the same time, 65 the speed-responsive device—the governor

G—may be connected to the rheostat R₂ in series with a field winding F so as to progressively short-circuit parts or the whole of such rheostat R₂ in accordance with variations in the speed of the roll. These 70 modifications are all clearly illustrated in Fig. 3 and are alternative connections to those of Fig. 2. In this manner there will be secured a retarding effect imposed upon the roll which will be greatest as the press-speed is being reduced. 75

Another improvement secured through our invention is in the automatic reduction of the resistance of the external circuit to the armature A of the generator 14 as the 80 generator speed is reduced. It will be understood that the decrease of speed of rotation of the roll of paper—as the press-speed is cut down—is accompanied by a decrease of generator speed; this, in turn, decreases 85 the generator voltage developed and this diminishes the current output through the resistance R₁. We prefer to counter-balance this decrease in generator voltage, within practical limits, by automatically cutting out—as by short-circuiting—portions of the rheostat R₁ forming the external circuit for the armature A. This may be done by utilizing the centrifugal governor G of Fig. 2, driven from the web-roll either directly 90 or indirectly, as from the shaft 10. As the web-roll speed decreases the weights of the centrifugal governor G force down the end of the regulating arm of the switch S, causing the other end of such arm to traverse 95 a succession of switch contacts which either directly or through relay switches will progressively short-circuit sections of the rheostat R₁. We do not wish to limit ourselves to the precise electrical connections 100 shown as various modifications thereof are possible in the following of our invention. 105

What we claim is as follows:

1. A tension device for newspaper roll stands comprising a frame pivoted at one 110 end, a pulley at each end of said frame, a belt carried by said pulleys and contacting with and driven exclusively by a roll of paper carried by the roll stand, a shaft driven by one belt pulley, a dynamo connected to said shaft, a resistance to receive and limit the dynamo current to impose a dynamic braking upon said shaft and means for automatically increasing the dynamo output when the press is to be stopped. 115

2. A tension device for newspaper roll stands comprising a frame pivoted at one end, a pulley at each end of said frame, a belt carried by said pulleys and contacting with and driven exclusively by a roll of paper carried by the roll stand, a dynamo receiving its driving power from such belt, and means for increasing the load upon the dynamo when the press is to be stopped. 125

3. An electrodynamic tension apparatus 120

for the web roll of a printing press comprising a belt driven by contact with such roll, a dynamo electric generator receiving its driving power from such belt, a rheostat connected to one of the generator elements to limit the normal current flow therethrough, and means for changing the effective resistance of such rheostat when the press is to be decelerated.

10 4. An electrodynamic tension apparatus for the web roll of a printing press comprising a belt driven by contact with such roll, a dynamo electric generator receiving its driving power from such belt, an external 15 load circuit for such generator, a speed-responsive device actuated by the web-roll and a switch controlled by the speed-responsive device for varying the effective resistance of the external load circuit of the generator.

20 5. An electrodynamic tension apparatus for the web-roll of a printing press comprising a belt driven by contact with such roll, a dynamo electric generator receiving its driving force from such belt, a rheostat 25 connected to one of the generator elements to limit the current flow therethrough, a speed-responsive device actuated by the web-roll and a switch controlled by the speed-responsive device for varying the effective 30 resistance of such current limiting rheostat.

35 6. An electrodynamic tension apparatus for the web-roll of a printing press comprising a belt driven by contact with such roll, a dynamo electric generator receiving its driving power from such belt, a resistance device connected to one of the generator elements to limit the current flow therethrough, means for changing the electrical constants of that circuit when the press is to be 40 stopped, a second resistance device connected to the other generator element, a speed-responsive device actuated by the roll and a switch controlled by the speed-responsive de-

vice for varying the effective resistance of such second resistance device.

45 7. A tension device for newspaper roll stands comprising a frame pivoted at its upper end, a pulley at each end of said frame, a belt carried by said pulleys and contacting with and driven exclusively by a 50 roll of paper carried by the roll stand, a shaft driven by said upper belt pulley, a dynamo driven from said shaft, a resistance through which the dynamo current passes to impose a dynamic braking upon said 55 shaft, and means for automatically reducing the resistance when the shaft speed is reduced.

8. An electro-dynamic tension apparatus for the web roll of a printing press comprising a belt driven by contact with such roll, a dynamo electric machine receiving its driving power from such belt, a resistance connected to the armature circuit to receive and limit the current flow therefrom, and 60 means for changing the electrical constants of that circuit when the press is to be stopped.

65 9. An electro-dynamic tension apparatus for the web roll of a printing press comprising a belt driven by contact with such roll, 70 a dynamo electric generator receiving its driving power from such belt, a resistance device connected in the field circuit to limit the current flow therethrough, means for changing the electrical constants of that circuit when the press is to be stopped, a second 75 resistance device connected to the armature to receive and limit the current flow therefrom, a speed-responsive device actuated by the roll and a switch controlled by the 80 speed-responsive device for varying the effective resistance of the armature resistance device.
